UNITED STATES PATENT OFFICE.

JAMES E. KELLY, OF ASCO, WEST VIRGINIA, ASSIGNOR OF ONE-HALF TO JOE S. HARPER, OF ASCO, WEST VIRGINIA.

RAILROAD TIE.

Application filed September 20, 1926. Serial No. 136,573.

This invention relates to a tie for mine railroads, the general object of the invention being to provide means for holding a pair of extension rails on their sides, with 5 their treads abutting the end rails of a track so that the wheels of a car can pass from the said end rails upon the upset rails so that the said upset rails form a continuation of the track.

10 A further object of the invention is to so form the holding means for the upset rails that they can be easily and quickly loosened to permit the upset rails to be moved longitudinally to either lengthen or shorten the 15 track, as desired.

Another object of the invention is to provide the improved tie with a pair of pivoted locking members, each of which, in one position, will hold an end rail to the tie 20 and in another position will reinforce a member which supports the tread of the upset rail and which normally engages the base flange of an end rail.

This invention also consists in certain 25 other features of construction and in the combination and arrangement of the several parts, to be hereinafter fully described, illustrated in the accompanying drawings and specifically pointed out in the appended 30 claims.

In describing my invention in detail, reference will be had to the accompanying drawings wherein like characters denote like or corresponding parts throughout the 35 several views, and in which:—

Figure 1 is a view showing a track with my improved ties in use supporting a pair of extension rails.

Figure 2 is a section on line 2—2 of Figure 1.

Figure 3 is a fragmentary plan view showing an end rail and an upset rail, with the locking means for securing them to a tie.

Figure 4 is a section on line 4—4 of Figure 1.

Figure 5 is a fragmentary plan view of a tie.

Figure 6 is a section on line 6—6 of Figure 3.

In these views, 1 indicates the end rails of a track and 2 indicates one of the ties of the said track. The ties forming the subject matter of my invention are shown at 3, and the upset rails supported by these ties, are shown at 4. The ties are of channel

shape in cross section, as shown in Figure 6, though they may be of any desired shape. Each tie, adjacent each end thereof, carries a locking lever 5 which is pivotally connected to the tie by the pivot pin 6, the stationary supporting member 7 which is riveted to the tie and is undercut, as shown at 8, and the pivoted holding member 9 which is pivotally secured to the tie by the bolt 10. A reinforcing plate 11 is placed on the under face of the top of the tie and is perforated to receive the pin 6, the rivets and the bolt 10. The lever 5 has one end undercut to form the recess 12 which engages a portion of the base of one of the end rails 13 so as to help hold the said rail to the tie while the other end of the lever is provided with a beveled part 13 which is adapted to engage the recess 8 formed by the undercut of the member 7 when the lever is turned 75 end for end. When the lever is in this position, it will fill the recess 8 and thus reinforce the member 7 and prevent tilting movement of the same under the weight of the car. This member 7 receives the tread 80 part of the upset rail 4 and its outer end is beveled to form an abutting surface for a part of the base of the rail, as clearly shown in Figure 4. The member 9 is formed with a vertical part 14 for abutting the under face of the rail 4 and this part is provided with a hook-shaped upper end 15 for engaging the upper edge of the base of the rail 4.

From the foregoing, it will be seen that each rail 4 is supported with its web in horizontal position and with its tread abutting the rail 1 so that the flange of a car wheel will engage the under part of the tread of the rail 4 as the tread of the wheel rides over the tread of the rail 1. Thus when the wheel runs off the rail 1, it will still be supported by the rail 4 and there will be no shocks or bumps as the wheel passes from one rail to the other. Each rail 4 is firmly supported by the members 7 and 9 so that there can be no movement of the rail, but when the rail is to be moved longitudinally in order to extend the track or to shorten the same, the nuts on the bolts 10 are loosened so that the members 9 on the ties will release each rail to permit the same to be moved longitudinally. After the rails have been adjusted, the nuts of the bolts 10 are tightened again to clamp the rails in position. As will be understood, the levers 5 on

the ties which are supporting the end rails 1 are turned so that their recessed ends are engaging the bases of the rails 1, as shown in Figure 2, but those levers of the ties 5 which are only supporting the rails 4 are turned so that their beveled ends 13 will engage the recesses 8 of the members 7, as shown in Figure 4.

It will be seen that my improved ties will 10 firmly hold a pair of rails in upset position alongside the end rails of the track so that a car can pass from the said end rails upon the upset rails and vice versa and it will also be seen that the holding means can be easily 15 and quickly loosened to permit adjustment of the upset rails when the track is to be extended or shortened. It will, of course, be understood that as the track is being extended, the ties 3 are moved to the extended 20 portion of the track and an ordinary tie substituted therefor. It will also be understood that when the track has been extended a sufficient distance to receive an ordinary pair of rails, then these rails are put in place 25 on ordinary ties and the upset rails are used when it again becomes necessary to extend the track, the improved ties being arranged at the outer ends of the end rails.

While this invention is mainly designed 30 for use in mines, it will, of course, be understood that it can be used in other places and it is useful in connecting a curved part of a track with a straight part and where it is necessary to move the curved part inwardly 35 and outwardly, for instance, in keeping the track close to a room pillar in a mine.

It is thought from the foregoing description that the advantages and novel features of my invention will be readily apparent.

40 I desire it to be understood that I may make changes in the construction and in the combination and arrangement of the several parts, provided that such changes fall within the scope of the appended claims.

45 What I claim is:—

1. Means for supporting a pair of upset rails alongside a pair of upright rails, comprising a number of ties, a holding member adjacent each outer end of each tie, a supporting member passing through the tie ad-

jacent each holding member and a lever pivoted to each end of each tie and having a recess at one end for engaging a part of the base of an upright rail, when the lever is used for holding an upright rail in position and a beveled part at its other end for passing under the supporting member to reinforce the same when the lever is used in connection with an upset rail.

2. Means for supporting a pair of upset rails alongside a pair of upright rails comprising a number of ties, a holding member adjacent each outer end of each tie for clamping the base part of each upset rail to the tie, means for detachably connecting each holding member to the tie, a supporting member fastened to the tie adjacent each holding member so that the base flange of an upset rail will fit between the two members, with the edge of the tread of the upset rail resting upon the supporting member and a lever pivoted to each end of each tie and having a recess at one end for engaging a part of the base of an upright rail and a beveled part at the other end for passing under the supporting member to reinforce the same.

3. Means for supporting a pair of upset rails alongside a pair of upright rails comprising a number of ties, each having a lever pivoted to each end thereof, one end of the lever being recessed to engage a part of an upright rail and the other end being beveled, a supporting member fastened to each end of each tie and having an undercut part forming a recess for receiving a beveled end of the lever, said supporting member forming a rest for the tread of an upset rail and a holding member bolted to each end of each tie and having a vertical part for engaging the under face of the base of an upset rail with a hook at the upper end of the vertical part for engaging a part of the base flange of an upright rail, said holding member and supporting member forming a space for receiving a part of the base flange of an upset rail.

In testimony whereof I affix my signature.

JAMES E. KELLY.
